UNITED STATES PATENT OFFICE.

GEORGE F. CAREY, OF NEW YORK, N. Y.

DESIGN FOR A TIP FOR HAY-FORKS.

SPECIFICATION forming part of Design No. 29,068, dated July 19, 1898.

Application filed November 22, 1897. Serial No. 659,521. Term of patent 3½ years.

To all whom it may concern:

Be it known that I, GEORGE FRANCIS CAREY, a citizen of the United States, residing at New York city, in the county and State of New York, have invented and produced a new and original Design for a Tip for Hay-Forks, of which the following is a specification, reference being had to the accompanying drawings, in which—

10 Figure 1 is a perspective view, and Fig. 2 is a side elevation, of a tip for hay-forks, showing my new design.

15 The leading or material feature of my design consists of the tip for hay-forks forming the subject-matter of the accompanying illustrations. As shown in the drawings, the tip has an upper cylindrical portion which extends with its sides on parallel lines for a considerable distance compared with the length 20 of the tip and unite with the converging lines,

which extend on straight lines, forming a tapering portion which is brought to a sharp point, the entire surface of the tip being smooth and it presenting a cavity at the free end of its cylindrical portion. 25

Referring to the drawings by letters, the cylindrical portion A has at its top D the cavity E and has its sides formed on parallel lines to their juncture with the tapered portion B of the tip. 30

Having described my invention, what I claim as new, and desire to secure by Letters Patent, is—

The design for a tip for hay-forks, as herein shown and described.

GEORGE F. CAREY.
